UNITED STATES PATENT OFFICE.

FREDERICK N. TAFF, OF MILLINGTON, NEW JERSEY.

CIGARETTE AND CIGAR HOLDER.

Application filed April 18, 1922. Serial No. 554,857.

To all whom it may concern:

Be it known that I, FREDERICK N. TAFF, a citizen of the United States, residing at Millington, in the county of Morris and State of New Jersey, have invented an Improvement in Cigarette and Cigar Holders, of which the following is a specification.

My invention relates to a device for holding a cigarette or cigar while being smoked, and its object is to provide an ejector within the holder which will not interfere with the draft passage while smoking, but which may be operated with facility for pushing the butt or short end of a cigarette or cigar from the holder.

The details of the invention are herein-after particularly described.

In the accompanying drawing:—

Figure 1 is an elevation of a cigarette or cigar holder embodying my invention.

Fig. 2 is a section on the broken line 2—2 of Fig. 1.

Fig. 3 is a similar view showing the ejector in extended position.

Fig. 4 is a view looking into the receiving end of the holder, the ejector being removed, and

Fig. 5 is a longitudinal section through the holder, showing a modification.

All the figures are in enlarged size.

Similar reference characters denote like parts throughout the several figures.

The main body of the holder may be of any convenient size or exterior shape, and while I have illustrated it as of one piece and prefer to so make it, the mouth piece or bit may, if desired, be a separate piece and screwed onto the body in the ordinary manner.

The main body portion 10 of the holder is provided at one end with a mouth piece or bit 11, provided with the usual draft passage 12.

The opposite end of the holder is provided with an opening 13 of a size to receive the end of a cigarette or cigar; this opening is circular and of uniform diameter for a predetermined distance from the end of the holder, beyond which point the diameter is

gradually lessened by curving the bore inwardly for a predetermined distance forming an annular curved recess 14. The bore is from this point continued for a predetermined distance of uniform diameter, providing a circular opening 15 of smaller diameter than the opening 13, and also pro-

viding at the inner end of this opening 15 an annular shoulder 16.

The bore is then continued of uniform diameter for another predetermined distance 60 forming a circular passage way 17, at the inner end of which this portion is gradually curved inwards forming a cup shaped recess 18 communicating with the draft passage 12 in the mouth piece.

A spiral slot 19 is cut in the top of the body portion 10 of the holder, which is of a length approximately the length of the parallel sided opening 13 in the end of the holder.

20, indicates the ejector, which is of a shape to closely fit the interior shape of the body 10 of the holder below its mouth, that is, the exterior of the ejector head 21, is curved inwardly to conform to the curved 75 interior surface of the annular recess 14, into which it is to fit and be seated when the ejector is in a normal position as shown in Fig. 2. The ejector extends beyond the socket or recess 14, in uniform diameter for 80 a certain distance and fits the passage way 15, in the body 10, being offset at 22, to seat against the annular shoulder 16, on the holder beyond which it extends in reduced uniform diameter to fit the bore at this point 85 in the holder, its extreme inner end 23 being curved inwardly to closely fit into and seat within the cup shaped recess 18. The ejector is provided with a central longitudinal draft passage 24, registering with the draft pas-

90 sage 12 in the mouth piece 11, and communicating with the opening 13, in the forward end of the body 10. The front end of the draft passage 24 in the ejector is preferably slightly flaring to enlarge the draft 95 passage at that end, although this is not necessary.

A pin or screw stud 25, passes through the spiral slot 19, in the body 10, being slidable therein and provided with a suitable head 100 26, which serves as a finger grip in manipulating the ejector. The lower end of this pin or stud is exteriorly threaded and is screwed into a threaded hole in the body of the ejector.

When the pin or stud 25 is moved forward, it carries the ejector forward within the holder, lifting the inclined portions 21 and 23 from their seats in the annular recess 14, and cup shaped recess 18, when the 110 continued forward movement of the ejector will push a cigarette or cigar butt from the

- mouth of the holder, without the necessity of touching the butt with the fingers. The pin or stud 25 is then moved backward in the slot 19, drawing the ejector back within the holder until its inclined head 21 and inner end 23 again seat within the annular recess 14 and cup shaped recess 18, shutting off any possible draft passage between the exterior surface of the ejector and the interior surface of the holder. Owing to the shape of the slot 19, the ejector is given a turning movement which aids in more closely seating its inclined head and inner end with the sockets 14 and 18.
- 10 15 The ejector may be readily withdrawn from the holder for cleaning or other purposes, by simply unscrewing the pin or stud 25.

20 While I prefer to provide the annular shoulder 16, on the interior of the holder, this may be dispensed with, and that portion of the bore between the annular recess 14, and cup shaped recess 18, be of uniform diameter, the diameter of the ejector between these points being made to correspond as illustrated in Fig. 5.

25 My invention provides a holder in which a cigarette or cigar may be smoked to a short butt and then ejected from the holder without liability of soiling or burning the fingers; the draft is only through the center of the holder, and the ejector being entirely inside of the holder is concealed from view, and in no way detracts from the appearance 30 of the holder.

35 I claim as my invention.

1. A holder for cigarettes or cigars provided with a spiral slot, and having an interior annular socket with an inclined wall, 40 a cup shaped recess beyond said socket and an intermediate passage way, an ejector fitting therein and provided with an inclined head to seat into said annular socket and having its inner end inclined to seat into 45 said cup shaped recess, and a stud passing through said spiral slot in the holder with its inner end removably secured to the ejector.

2. A holder for cigarettes or cigars comprising a body provided with a spiral slot, 50 and having a mouth piece at one end provided with a central longitudinal draft passage, the forward end of said body having an opening to receive one end of a cigarette or cigar, the inner end of said opening being 55 inclined inwardly forming an annular socket with a central opening extending a predetermined distance of uniform diameter, and terminating in a cup shaped recess having a central opening in register with the draft 60 passage in the mouth piece, an ejector provided with a central draft passage, and an inclined head to seat within said annular socket in the body portion, and having its inner end inclined to seat into said cup 65 shaped recess in the holder, and a stud passing through said spiral slot in the holder with its inner end removably connected to the ejector.

3. A holder for cigarettes or cigars, 70 comprising a body portion provided with a spiral slot, and having a mouth-piece at one end provided with a central longitudinal draft passage, the forward end of said body having an opening to receive a cigarette or 75 cigar, the inner end of said opening being inclined inwardly forming an annular socket with a central opening extending a predetermined distance of uniform diameter, an annular shoulder at the inner end thereof, 80 said opening extending therefrom in uniform smaller diameter and terminating in a cup shaped recess having a central opening in register with the draft passage in the mouth piece, an ejector provided 85 with a central draft passage and an inclined head to seat within said annular socket in the body, fitting the opening in the holder beyond said socket, and having its inner end inclined to seat into said cup shaped recess in the holder, and a stud passing through said spiral slot in the holder with its inner end removably connected to the ejector.

Signed by me this 12th day of April 1922.
FREDERICK N. TAFF.
